ATTORNEY.

UNITED STATES PATENT OFFICE

CLAUDE E. SPALDING, OF RICHMOND, CALIFORNIA.

CONCRETE-FORM BOARD.

1,383,161.

Specification of Letters Patent. Patented June 28, 1921.

Application filed May 28, 1920. Serial No. 384,984.

To all whom it may concern:

Be it known that I, CLAUDE E. SPALDING, a citizen of United States, residing at Richmond, in the county of Contra Costa and 5 State of California, have invented new and useful Improvements in Concrete-Form Boards, of which the following is a specification.

This invention relates to an improvement 10 in forms of the collapsible type.

The principal object of this invention is to construct a form which may be used in various places and which may be readily assembled and disassembled without the usual 15 difficulties now encountered.

Another object of this invention is to produce a form which may be used in concrete construction and the like, and one which is adjustable at various distances without the 20 necessity of sawing and fitting, which is now necessary.

Another object of this invention is to produce a form which may be readily assembled and quickly removed and again utilized in 25 the formation of other concrete structures.

A still further object of the invention is to produce a form, which is simple and reliable in operation, cheap to construct, strong and durable and capable of being handled by the 30 most inexperienced labor.

Other objects and advantages of the invention will be apparent during the course of the following description.

In the accompanying drawing forming a 35 part of this invention and in which like numerals are employed to designate like parts throughout the same;

Figure 1 is a perspective view of a top rail for the form.

40 Fig. 2 is a section of a form, having my invention applied thereto.

Fig. 3 is a top plain view looking down upon the parts shown in Fig. 2.

In the accompanying drawing wherein for 45 the purpose of illustration is shown a preferred embodiment of my invention, the numeral 5 designates a sill or foundation which is adapted to be placed in contact with the ground, floor or other like supports adjacent 50 to the point where the form is to be set up, while strips 6 and 7 are attached to the sill 5 and are spaced one from the other so as to form a groove 8 therebetween.

The numeral 10 designates a form-board 55 having beveled edges 11 and 12, while a

second form-board 13 is also provided with the beveled edges 14 and 15.

By referring to Fig. 3, it will be noted that the beveled edges 12 and 15 abut each other, thus forming a lap joint between the 60 form-boards 10 and 13.

A form-board 16 is provided with a beveled edge 17, which edge is adapted to abut the beveled edge 14 of the form-board 13. It will be noted, however, that this 65 form-board 16 differs from the form-board 13 in that it has an edge 18 formed at right angles to its front and back surfaces, the purpose of which is to allow the mounting of springs 19, 20 and 21 thereon, which 70 springs are held by suitable fastening means 19'.

The numeral 21' designates a form-board constructed similar to the form-board 16, i.e., having one vertical flat edge and a vertical beveled edge, which beveled edge is designated by the numeral 22 and is adapted to abut the beveled edge on the adjacent form-board 23. This combination of form-board may be carried out indefinitely, but for 80 the purpose of illustrating my invention, I believe the simple illustration and description given is sufficient.

It will be observed that plate 24 is attached to the form-board 21 in any convenient manner. Here I have shown nails 26 passing through the plate 24 and into the form-board 21. This plate 24 is of sufficient width to cover any opening which may be provided between the vertical surfaces of form-boards 16 and 21 and will also serve to prevent the passage from one side of the form to the other of concrete before it has become solidified.

Referring to Fig. 1, it will be noted that 95 I have constructed a grooved member 27 of two parallel pieces having a spacer 28 therebetween. This grooved member 27 is adapted to be placed upon the tops of the form-boards 21 so as to hold the same in proper 100 alinement. The action of my form-boards is as follows:

Assuming it is desired to build a form 5 feet 3 inches long, and the form-boards are 6 inches in width, it would take ten and a 105 fraction boards under ordinary conditions. By using my form-boards and two form-boards having an expansion joint therebetween I am able to accommodate for the odd size of 5 feet and 3 inches. The same is true 110

under all conditions, it merely being necessary to insert one or more expansive joints to care for various conditions.

In operation the form-boards are set up 5 as shown in Fig. 2 and the expansion of springs 19, 20 and 21 causes the beveled edges of the various forms to be brought into intimate contact one with the other for the purpose of forming a tight joint, and 10 which springs also function as a contracting means therefore, details of which function will be hereinafter described.

When the form is assembled, cement may be poured against the form boards and 15 allowed to harden. After the hardening or setting has been completed, the form-boards may be removed by knocking off the grooved member No. 27 and the strip 28. Then by exerting pressure on the respective boards 20 10 and 23 the springs 19, 20 and 21 will contract and the form-board 13 can be thus easily separated from the form proper. The extraction of one of the form-boards will thus allow the remaining boards to come 25 away from the cement without difficulty or mutilation. The sill 5 and strip 6 may be left in the air space which exists between the respective walls constructed by means of my improved form.

30 It will be noted that this form may be employed where the usual form is cumbersome, expensive to transport and in many instances unobtainable; and it will be further evident that there is here provided a form 35 which may be placed upon the market and sold at a very reasonable price.

Thus it will be seen that by employing the combination of the beveled boards in conjunction with springs and a metal plate, I 40 have provided not only a novel form, but also one which owing to the contraction and expansion of the spring elements allows firstly the construction of a compact form, and secondly the easy extraction of the 45 boards so that they may be used when desired when setting up for another form.

Attention is called to the fact that I have herewith shown only one form, but it is to be understood that this form is to be used in conjunction with another form of similar configuration, which two forms serve to construct an inner wall. By the employment of these forms I have overcome the objections experienced by builders in the use of 55 hollow concrete blocks, for the blocks in use today have been anything but satisfactory owing to the expense entailed in laying out the same, and the additional fact that water will pass through the concrete blocks and accordingly dampen the inner walls when the 60 blocks are joined together, unless a moisture-proof plastic is utilized. It will be ap-

parent that by the use of my improved form or plurality of forms by which a solid inner wall is constructed, the additional expense incurred by the necessity of a moisture-proof plastic is avoided, and yet the inner wall can be preserved in an absolutely dry state. It will furthermore be apparent that by the provision of an air space between the walls, there will be afforded by the application of my improved form a building construction which is cooler in summer and warmer in winter.

It is to be understood that the form of my 75 invention herewith shown and described, is to be taken as a preferred example of the same, and that various changes in the shape, size and arrangement of parts may be resorted to without departing from the spirit 80 of the invention or the scope of the subjoined claims.

Having thus described the invention, I claim:—

1. In a form, a sill, parallel members attached to said sill, a series of form-boards having beveled edges formed on said boards, and expansion means for keeping the beveled edges of said boards in contact one with the other and for allowing an easy extraction of said form-boards.

2. In a form, a sill, parallel members attached to said sill, form-boards having their lower ends positioned on said sill, beveled edges provided on said form-boards, a pair 95 of intermediate form-boards having a single beveled edge and single vertical flat edge, a groove member adapted to engage the upper ends of said form-boards and said intermediate boards, and expansion means being adapted to keep said beveled edges of said form-boards to contact one with the other and to allow an easy extraction of said form-boards.

3. In a form, a sill, parallel members attached to said sill, form-boards having their lower ends positioned on said sill, beveled edges provided on said form-boards, a pair of intermediate form-boards having a single beveled edge and a single vertical flat edge, 110 a groove member adapted to engage the upper ends of said form-boards and said intermediate boards, expansion means between said vertical flat faces, said expansion means being adapted to keep said beveled edges 115 of said form-boards to contact one with the other and to allow an easy extraction of said form-boards, and a plate adapted to be attached to one of said intermediate boards and to over-lap the other of said intermediate boards.

In testimony whereof I affix my signature.

CLAUDE E. SPALDING.
